T. J. FARRINGTON

WATER HEATING DEVICE

Filed Nov. 10, 1926

Fig. 2.

Inventor
Telford Jones Farrington

By Clarence A. O'Brien
Attorney

UNITED STATES PATENT OFFICE.

TELFORD JONES FARRINGTON, OF KERRVILLE, TEXAS.

WATER-HEATING DEVICE.

Application filed November 10, 1926. Serial No. 147,515.

The present invention relates to water heating devices of the so-called instantaneous type wherein opening of a faucet automatically induces the operation of the heating device which acts upon the flowing stream to raise the water to the desired temperature, and closing of the faucet automatically stops the operation thereof. The present invention illustrates an instantaneous heater wherein the current is turned on and off by changes in the pressure of the water without employing any electric connection to the faucets or valves by which the flow is controlled.

15 An important object of the invention is the provision of an apparatus of this type of simple and rugged construction which shall be cheaply made, readily cleaned, reliable in operation, and economical of current.

20 Another very important object of the invention is to provide a structure of this nature which is exceedingly compact and in which the parts may be readily assembled and disassembled when desired thereby making the parts very accessible for repairs and replacement purposes.

With the above and numerous other objects in view, as will appear as the description proceeds, the invention resides in certain novel features of construction, and in the combination and arrangement of parts as will be hereinafter more fully described and claimed.

In the drawing:

35 Figure 1 is a sectional elevation of the water heater embodying the features of my invention.

Fig. 2 is a transverse section therethrough taken substantially on the line 2—2 of Fig. 40 1 looking downwardly.

Referring to the drawing in detail it will be seen that the control valve 1 is somewhat like the ordinary globe valve used for water and steam and is preferably constructed of brass. A housing 2 is screwed on the top of the valve body to support the heater and forms a convenient means of supplying a stuffing box 3 cast integral with the housing which prevents water leaking out around the valve stem 4. This valve stem 4 reaches to the top of the water heater as is clearly illustrated in the drawing and is provided with a porcelain cap or other insulating material so that when the valve raises off the valve seat it will cause the contact points 5 to come into engagement with each other

thus closing an electric circuit that will in turn cause the energization of the heating element to be referred to later. Suitable terminals 11 are provided to attach electric wires to and the contacts 5 can be arranged at the bottom of the electric heating element as well as at the top if so desired. When all faucets of the outlet pipe are closed, the water pressure in the same being equal on both sides of the valve 16 causes the valve to rest on the seat. This seat is not designed to hold pressure but is intended more as a stop or rest for the valve and valve stem. To overcome valve stem 70 packing friction and to give the valve a quicker motion, a spring 15 has been provided. A copper coil 10 is made so that the convolutions will lie close together and near the heating element. This coil connects with the control valve by a suitable connection 17 provided with union fittings. The outlet 19 will be provided with standard pipe threads to connect with the hot water piping in the building. The heating element is constructed of special resistant wires 6 and is held securely and is properly spaced with porcelain disks 7 and the whole is assembled on a brass pipe 8 which makes the heating element a separate part and can be inserted or removed without danger of damage. The center pipe 8 makes a convenient guide for the valve stem. The valve stem is insulated from the center pipe at the top in the way of a porcelain cap 4'. This can be substituted for any other suitable insulating material. The coils are covered with asbestos 9 and a suitable metal jacket 14 encloses the whole.

It is thought that the construction, utility, and advantages of this invention will now be clearly understood by those skilled in this art without a more detailed description thereof. Particular attention, however, is directed to the means with which the parts may be assembled and disassembled so as to make them accessible for repairs and replacement. The device is very simple in its construction and the parts are very compactly and conveniently arranged. The present embodiment of the invention has been disclosed in detail merely by way of example since in actual practice it attains the features of advantage enumerated as desirable in the statement of the invention and the above description. It will be apparent that changes in the details of construction, and

in the combination and arrangement of parts may be resorted to without departing from the spirit or scope of the invention as hereinafter claimed or sacrificing any of its advantages.

Having thus described my invention, what I claim as new is:

An instantaneous water heater of the class described including a casing, a water pipe 10 coiled in the casing with its convolutions in engagement with each other, a valve, a housing connecting the valve to the casing, a tube extending coaxially through the casing and

the coil in spaced relation to said coil, an electric heating element disposed about the 15 tube within the coil, a valve stem slidable in the tube, a circuit closure operatively connected with said valve stem and disposed within the casing and electrically associated in circuit with the electric heating element, 20 said valve stem being connected with said valve to be controlled thereby.

In testimony whereof I affix my signature.

TELFORD JONES FARRINGTON.
